CLAIM

The ornamental design of the bi-directional amplifier housing as shown and described.

DESCRIPTION

FIG. 1 is a perspective view of the bi-directional amplifier housing showing our new design;

FIG. 2 is a front elevational view thereof;

FIG. 3 is a back elevational view thereof;

FIG. 4 is a right side view thereof;

FIG. 5 is a left side view thereof;

FIG. 6 is a top view thereof; and,

FIG. 7 is a bottom view thereof.

The broken lines are included for the purpose of illustrating portions of the bidirectional amplifier and form no part of the claimed design.
